[57] CLAIM

The ornamental design for a flanged golf tee collar, substantially as shown and described.

DESCRIPTION

FIG. 1 is a top perspective view of a flanged golf tee
collar showing my new design;

FIG. 2 is an elevational view thereof;

FIG. 3 is a top plan view thereof;

FIG. 4 is a bottom plan view thereof;

FIG. 5 is a top perspective view of a flanged golf tee
collar showing a second embodiment of my new design;

FIG. 6 is an elevational view of FIG. 5;

FIG. 7 is a top plan view of FIG. 5; and

FIG. 8 is a bottom plan view of FIG. 5.
